UNITED STATES PATENT OFFICE.

ARTHUR C. HOPKINS, OF NILES, MICHIGAN, ASSIGNOR TO NATIONAL-STANDARD COMPANY, OF NILES, MICHIGAN.

LIFTING JACK.

Application filed March 26, 1927. Serial No. 178,589.

The main object of this invention is to provide an improved lifting jack of the toggle type which is very powerful, has a considerable throw, and may be compactly collapsed.

A further object is to provide a lifting jack of the class described which is economical in structure and at the same time strong and durable.

Objects pertaining to details and economies of my invention will appear from the description to follow. The invention is defined and pointed out in the claims.

A structure embodying the features of my invention is clearly illustrated in the accompanying drawing, in which:

Fig. 1 is a side view of my improved lifting jack collapsed.

Fig. 2 is a plan view thereof.

Fig. 3 is a vertical section on line 3—3 of Figs. 1 and 2.

Fig. 4 is a side elevation of the jack extended.

Referring to the drawing, I provide a T-shaped standard 1 having a suitable base 2. The standard is vertically slotted at 3 and the arms 4 are each made up of two members 5 connected by cross pieces 6 and 7 at their outer ends. It will be noted that the cross piece 7 is considerably longer than the cross piece 6. The cross pieces have pivots 8 at their ends.

The actuating screw 9 is provided with right and left hand threads at its ends and is arranged in the slot 3 and provided with thrust collars 10 supporting the screw against longitudinal movement while permitting it to move vertically in the slot 3.

Bell crank actuating levers 11 are mounted on the pivots 8, the short arms of these levers being connected by pivots 12 to the actuating members or nuts 13 having threaded engagement with the reversely threaded portions of the actuating screw.

Owing to the greater length of the cross piece 7 one pair of lifting levers is spaced farther than the other so that their ends are arranged in overlapping relation, the levers swinging in parallel planes.

Mounted on the inner ends of the levers by means of pivots 14 are pairs of lifting links 15 pivotally connected at their upper ends by means of the pivot rod 16, these links having outwardly projecting shoulders 17 adjacent their upper ends which form sup-

ports for the head member 18. This head member has projecting lugs 19 and 20 resting on the shoulders 17 and the lugs 20 are longer than the lugs 19 so as to engage the shoulders of the outer links.

The head member has downwardly projecting ears 21 disposed on the inside of the inner links and vertically slotted at 22 to engage the pivot pin 16. This allows for a relative vertical movement of the head member on the links, see Figs. 1 and 4, accommodating the swinging of the lifting links and consequent relative movement of their head supporting shoulders.

To permit complete collapsing the standard 70 is provided with a recess 23 in its upper end adapted to receive the pivot 16.

With the parts thus arranged I provide a powerful jack which may be very compactly collapsed and at the same time one 75 which is simple and economical in structure.

Having thus described my invention what I claim as new and desire to secure by Letters Patent is:

1. In a lifting jack, a T-shaped standard 80 provided with a base and having a vertical slot in the upright thereof, the arms of said standard terminating in transverse cross pieces provided with pivots at their ends, a right and left hand actuating screw disposed in said slot in said standard for vertical movement therein and provided with thrust collars coacting with the sides of the standard to support the screw longitudinally, actuating members on said screw, pairs 85 of bell crank lifting levers mounted on said pivots on said standard arms and pivotally connected to said actuating members, said cross pieces being of different lengths so that one pair of levers swings within the planes 90 of the other, pairs of links pivotally mounted on said lifting levers and pivotally connected to each other at their upper ends, said links being provided with outwardly projecting head supporting shoulders, and a head 95 mounted on said shoulders and provided with depending ears disposed between said links and vertically slotted to receive their connecting pivot, said standard having a recess in its upper end adapted to receive said 100 pin when the jack is fully collapsed.

2. In a lifting jack, a T-shaped standard provided with a base and having a vertical slot in the upright thereof, the arms of said standard terminating in transverse cross 110

pieces provided with pivots at their ends, a right and left hand actuating screw disposed in said slot in said standard for vertical movement therein and provided with thrust 5 collars coaxing with the sides of the standard to support the screw longitudinally, actuating members on said screw, pairs of bell crank lifting levers mounted on said pivots on said standard arms and pivotally connected 10 to said actuating members, said cross pieces being of different lengths so that one pair of levers swings within the planes of the other, and pairs of links pivotally mounted on said lifting levers and pivotally connected 15 to each other at their upper ends.

3. In a lifting jack, a T-shaped standard having a vertical slot in the upright thereof, a reversely threaded actuating screw disposed in said slot in said standard for vertical movement therein and provided with thrust collars supporting the screw against longitudinal movement, actuating members on said screw, bell crank lifting levers mounted on said standard arms in opposed 20 relation to swing in different planes with their inner ends in overlapping relation, links pivotally mounted on the inner end of said lifting levers and pivotally connected 25 at their upper ends, said links being provided with outwardly projecting head supporting shoulders, and a head mounted on said shoulders on said links and vertically slotted to receive their connecting pivot.

4. In a lifting jack, a standard, a reversely 30 threaded actuating screw mounted on said standard, actuating members on said screw, bell crank lifting levers mounted on said standard in opposed relation to swing in different planes with their inner ends in 35 overlapping relation, links pivotally mount-

ed on the inner end of said lifting levers and pivotally connected at their upper ends, said links being provided with outwardly projecting head supporting shoulders, and a head mounted on said shoulders on said links and vertically slotted to receive their connecting pivot.

5. In a lifting jack, the combination of a standard, a right and left hand horizontally disposed actuating screw mounted on said standard for vertical reciprocating movement and supported against longitudinal movement, actuating members on said screw, oppositely disposed lifting levers pivotally mounted on said standard pivotally connected 50 to said actuating members, said levers being disposed with their inner ends in overlapping relation and to swing in parallel planes, pairs of links pivotally mounted on the inner ends of said lifting levers and pivotally connected to each other at their upper ends, and a head mounted on the upper ends 55 of said links.

6. In a lifting jack, the combination of a standard, a right and left hand horizontally disposed actuating screw mounted on said standard for vertical reciprocating movement and supported against longitudinal movement, actuating members on said screw, oppositely disposed lifting levers pivotally 60 mounted on said standard and pivotally connected to said actuating members, pairs of links pivotally mounted on the inner ends of said lifting levers and pivotally connected to each other at their upper ends, and a head 65 mounted on the upper ends of said links.

In witness whereof I have hereunto set my hand.

ARTHUR C. HOPKINS.
